(57) **CLAIM**

The ornamental design for a pet hair carpet rake apparatus, as shown and described.

DESCRIPTION

FIG. 1 is a front perspective view of a pet hair carpet rake apparatus, showing my new design;

FIG. 2 is a rear perspective view thereof;

FIG. 3 is a bottom perspective view thereof;

FIG. 4 is a front perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof;

FIG. 11 is an enlarged detail view of area 11 in FIG. 3; and,

FIG. 12 is an enlarged detail view of area 12 in FIG. 4.

The broken lines in the drawings illustrate the portions of the pet hair carpet rake apparatus, which form no part of the claimed design.

The dash-dot-dash broken lines encircling the enlarged views are for annotative purposes only and form no part of the claim thereof.

1 Claim, 12 Drawing Sheets
